PORTABLE TYPE MAGNETIC TAPE RECORDING AND PLAYBACK APPARATUS OR SIMILAR ARTICLE

Gerhard Dietrich, Fuerth, Bavaria, Germany, assignor to
Max Grundig, Fuerth, Bavaria, Germany

Filed Dec. 5, 1967, Ser. No. 9,642

Claims priority, application Germany Oct. 30, 1967

Term of patent 14 years

(Cl. D26—14)

FIG. 1 is a perspective view of the apparatus showing the front, bottom, and right hand panel;

FIG. 2 is a front elevation of the apparatus shown in FIG. 1;

FIG. 3 is a side elevation showing the left hand panel; and

FIG. 4 is a top elevation of the apparatus shown in FIG. 1.

The dominant features of my design reside in the portions shown in full lines.

I claim:

The ornamental design for a portable type magnetic tape recording and playback apparatus or similar article, as shown and described.
